UNITED STATES PATENT OFFICE.

THOMAS J. BEARD, OF OMAHA, NEBRASKA.

WALL-PAPER EXHIBITOR.

SPECIFICATION forming part of Letters Patent No. 717,731, dated January 6, 1903.

Application filed June 11, 1901. Serial No. 64,147. (No model.)

To all whom it may concern:

Be it known that I, THOMAS J. BEARD, residing at Omaha, in the county of Douglas and State of Nebraska, have invented certain useful Improvements in Wall-Paper Exhibitors; and I do hereby declare that the following is a full, clear, and exact description of the invention, such as will enable others skilled in the art to which it appertains to make and use the same, reference being had to the accompanying drawings, which form a part of this specification.

This invention relates to a new and novel wall-paper exhibitor.

15 The object of my invention is to provide a device arranged to be used in exhibiting wall-paper, fabrics, and the like and being further adapted to be used as an advertising device, as will be described more fully herein-
20 after.

In the accompanying drawings, I have shown in Figure 1 a wall-paper exhibitor embodying my invention, disclosing a front view. Fig. 2 shows a side elevation, while Fig. 3 shows an enlarged detail, disclosing the method of securing the exhibits.

My invention embodies, essentially, two standards 2 2, which are supported by means of the brace-bars 3, 4, and 5 to impart rigidity 30 to the structure. Secured to these supports 2 are the bearings 7 7, which hold and support a shaft 6, provided with the collars a to prevent lateral displacement of the shaft. This shaft 6 has secured to it an ordinary 35 drum 10, preferably of wood, upon which drum are pasted, nailed, screwed, or otherwise secured a plurality of signs or advertising-frames A, below which are secured back to back the paper or fabric exhibits B, C to 40 be displayed.

In arranging my drum for the exhibit of specimens I cut a number of specimens of a suitable length, and these, if desired, may, if they are wall-paper, be fabric-backed, so as 45 to increase their life. They are then placed back to back, as is shown at B and C, and have one end placed below an advertising-frame A, by means of which they are secured to the exhibiting-drum 10. A suitable number 50 of such exhibiting-frames A may be used, and in the drawings a drum is shown large

enough to accommodate sixteen advertising-frames and ninety-six wall-paper specimens.

In referring to Fig. 1 it will be noticed that a center strip is marked as the border, the 55 exhibit upon one side being the wall and the opposite side the ceiling-covering, so that a purchaser has brought before him the combination of the wall, border, and ceiling, so that the effect may be better judged. 60

It will be noticed that the shaft 6 has secured to it a pulley K. This pulley may be used as a hand-wheel, by means of which the drum may be slowly revolved in order to display the samples, or this pulley K may be brought into 65 belt communication with certain power, so that the drum is slowly revolved.

In referring to Fig. 1, for instance, an advertising-frame A is shown, and below and depending from the same are a number of exhibits B, while above are shown a number of exhibits C. 70

In the use of my apparatus I provide a drag-bar 15, which is adapted to lightly work over the samples to keep them in a nice flattened 75 condition while they slide below the drag-bar, as is shown in Fig. 2. Now in revolving the drum the exhibits are successively brought under the drag-bar 15, which is secured to a supporting-bar b by means of the strands 13 80 13. The bar b is held by means of the standards 12. In this condition the specimens C above the center of the drum are shown, while below the center of the drum the exhibits or specimens B are disclosed, and between each 85 set of exhibits or specimens I secure an advertising-frame A.

In Fig. 2, for instance, above one of the frames A is shown an exhibit C and below said frame A an exhibit B. Now if the drum were 90 revolved the paper exhibit C would fall down to cover the lower exhibit B to permit two sets of new exhibits to come into view, as well as a new advertising-frame. The whole forms a neat, tasty, and striking display device, and 95 within the advertising-frames may be displayed the prices of the goods or information disclosing the number of yards of the goods and price-mark, &c., of a certain exhibit. The device, where the same is used as a window exhibit, is nicely adapted to display certain advertising matter held within the frames 100

A. The whole device forms a neat and simple construction and is readily operated.

Having thus described my said invention, what I claim as new, and desire to secure by 5 United States Letters Patent, is—

In a wall-paper exhibitor, the combination with the rotatable drum, the advertising strips or frames secured about said drum and arranged longitudinally thereof, the flexible 10 double-faced exhibits or samples secured at one edge to said drum and projecting from between said advertising-strips, a drag-bar located at the top of the drum and adapted to rest on the exhibits or samples, being so pro- 15 portioned and arranged with relation to each other and the drum that when an advertising-

strip is in position to be read the exhibit next above the same will be held by the drag-bar in position to expose one face and the exhibit next below will hang in position to expose one 20 face, whereby as the drum is rotated to bring the advertising-strips successively into reading position, the opposite face of the exhibit exposed above the strip will be exposed below the same, and a face of a new exhibit will 25 be exposed above said strip; substantially as described.

THOMAS J. BEARD.

In presence of—

GEORGE W. SUES,
R. J. DAVENPORT.
